(57) **CLAIM**

The ornamental design for a connector for a memory card, as shown and described.

DESCRIPTION

FIG. 1 is a front elevation view of our new design for a connector for a memory card;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a first perspective view thereof, including the top, left and front sides;

FIG. 8 is a second perspective view thereof, including the bottom, right and rear sides;

FIG. 9 is a third perspective view thereof, including the top, right and front sides;

FIG. 10 is a fourth perspective view thereof, including the top, right and rear sides;

FIG. 11 is a fifth perspective view thereof, including the top, left and rear sides; and,

FIG. 12 is a sixth perspective view thereof, including the bottom, left and front sides.
